(57) **CLAIM**

We claim the ornamental design for a light emitting diode lamp unit, as shown and described.

DESCRIPTION

FIG. 1 is a top perspective view of a first embodiment of a light emitting diode lamp unit of the present invention;

FIG. 2 is a top view thereof;

FIG. 3 is a bottom view thereof;

FIG. 4 is a first side view thereof, wherein the second side view is a mirror image thereof;

FIG. 5 is a third side view thereof, wherein the fourth side view is a mirror image thereof;

FIG. 6 is a top perspective view of a second embodiment of a light emitting diode lamp unit of the present invention;

FIG. 7 is a top view thereof;

FIG. 8 is a bottom view thereof;

FIG. 9 is a first side view thereof, wherein the second side view is a mirror image thereof; and,

FIG. 10 is a third side view thereof, wherein the fourth side view is a mirror image thereof.

The ornamental design which is claimed is shown in solid lines in the drawings. Any broken lines in the drawings are for illustrative purposes only and form no part of the claimed design.
